UNITED STATES PATENT OFFICE.

WILLIAM KELSO, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

PIPE-CARRIER FOR RAILWAY-CARS.

1,366,187.

Specification of Letters Patent. Patented Jan. 18, 1921.

Application filed November 4, 1920. Serial No. 421,757.

To all whom it may concern:

Be it known that I, WILLIAM KELSO, a citizen of the United States, residing at Pittsburgh, in the county of Allegheny and State of Pennsylvania, have invented certain new and useful Improvements in Pipe-Carriers for Railway-Cars; and I do hereby declare the following to be a full, clear, and exact description of the invention, such as will enable others skilled in the art to which it appertains to make and use the same.

My invention relates to pipe carrier mechanism for railway cars and is designed to provide simple, durable and efficient means for supporting the steam, air and signal pipes in a manner permitting their ends to be shifted transversely of the car to the extent required to prevent them from being struck or damaged by the head of a laterally swinging car coupler in any of the various positions which the latter may assume in service.

Generally stated, the principal feature of my invention consists in supporting a plurality of independently movable pipe clamps or pipe carriers by means of links or hangers which are pivotally connected to the car on opposite sides of the car coupler, means actuated by the lateral swinging movements of the coupler being provided for independently shifting the carriers in opposite directions in accordance with the movement of the coupler. In the embodiment of this feature of my invention in the mechanism 35 it is preferred so to arrange the pivoted hangers by which the pipe carriers are supported that the latter have a bias or normally tend to move toward the coupler.

There are minor features of the invention, residing in particular combinations and in details of construction, all as will herein-after appear.

In the drawings illustrating the form in which I prefer to embody the principle of my invention, the scope whereof is pointed out in the claims:—

Figure 1 is a view partly in plan and partly in horizontal section of a pipe carrier supporting mechanism constructed in accordance with the invention, illustrating its relation to the steam, air and signal pipes and to a lateral swinging coupler, the cou-

pler carry iron and the center sills of a car, a portion of the coupler head being broken away.

Fig. 2 is a section on the line 2—2, Fig. 1, the push bars by means of which the coupler causes the lateral shifting of the pipe carriers being shown in elevation.

In the drawings, 1 is a car coupler which is adapted to be mounted upon a railway car so as to be capable of swinging laterally when passing around curves in the track. The form of laterally swinging coupler illustrated in the drawings is of the well known type employing spring boxes 2 for normally maintaining the coupler stem in the longitudinal axis of the car and having its coupler head 3 pivotally connected to said stem by means of a pivot pin 4; but it will be understood that the laterally swinging coupler may be of other specific form if desired.

The coupler is supported by a carry iron 5 which extends between the center sills or draft sills 6 of the car. As a convenient means for securing the carry iron in position in a manner permitting it to be readily removed, it is preferred to attach rigidly to each of the draft sills, as by means of rivets 7, a bracket member 8, each of said brackets being provided with an inwardly extending perforated lug 9 upon which the carry iron 5 rests. Bolts 10, which pass through the perforations in the lugs 9 and through the carry iron, serve to retain the latter in assembled position.

Rigidly mounted upon the car on opposite sides of the center sills thereof are a pair of brackets 11 from which are pivotally suspended links or hangers 12 and 13, respectively. The pivotal connection of the links to the brackets 11 may be formed by rivets 14. The lower end of the hanger 12 is pivotally attached to a pipe carrier or pipe clamp 15 in which the steam pipe 16 is secured, while the corresponding end of the hanger 13 is similarly attached to a pipe carrier or clamp 17 by which the air pipe 18 and the signal pipe 19 are embraced. Rivets 20 may conveniently be employed as pivot pins for connecting the hangers 12 and 13 to their respective pipe clamps, which latter, as shown, are customarily constructed of

separable parts bolted together. As is shown in the drawings, the hangers 12 and 13 preferably converge upwardly, that is to say, the lines connecting the pivot pins 14 and 20 of the respective hangers converge upwardly. By this means the pipe carriers 15 and 17 are caused to have a normal bias or tendency to move inwardly toward the coupler.

10 The several pipes 16, 18 and 19 are secured to the car by clamping or otherwise, in the usual or any preferred manner, at a sufficient distance from their outer ends to permit their end portions to be deflected toward the sides of the car when the pipe carriers in which they are mounted are shifted laterally in response to the swinging movements of the coupler.

15 The means preferably employed for actuating the pipe carriers are transversely extending bars 21 one of which is pivotally connected to each of the carriers, such pivotal connection preferably being effected by rivets 22 which pass through perforations in 20 the outer ends of the bars and their respectively adjacent pipe clamps. Each of the bars 21 engages the stem of the car coupler 1, but preferably is not secured thereto, the result being that the coupler may effect a 25 lateral shifting of either bar independently of the other and, consequently, may independently shift either of the pipe carriers transversely of the car. The bars 21 extend through suitable openings 23 in the sills 6 30 and in the carry iron supporting brackets 8 and may rest upon the upper surface of the carry iron, the openings 23 being sufficiently 35 large to afford proper clearance for the bars 21 during their movements in the operation 40 of the mechanism.

45 The construction being substantially such as hereinbefore pointed out, its operation will be as follows: Upon a lateral swinging movement of the coupler one of the bars 21, depending upon the direction in which the coupler swings, is moved transversely, thus causing the pipe carrier to which it is 50 pivotally connected to be correspondingly shifted transversely of the car. Owing to 55 the fact that the pipe carriers 15 and 17 are suspended by the pivoted hangers 12 and 13, respectively, the outward transverse shifting of the pipe carrier causes the latter to be raised slightly. When the coupler 1 returns to its normal position in the 60 longitudinal axis of the car, the resiliency of the pipe or pipes which have been flexed causes the corresponding carrier to be returned to normal position, its restoration to such position being assisted by gravity as 65 the hanger by which the carrier is supported swings downwardly to its initial position.

My invention provides an extremely simple mechanism for preventing the coupler

head of lateral swinging couplers from striking against the angle cocks of the pipes, which frequently causes the breaking of said angle cocks and the disruption of the hose connections.

70

I claim:—

1. In mechanism of the character indicated, the combination with a laterally swinging car coupler, of a plurality of pipe carriers disposed upon opposite sides 75 of said coupler, means carried by the car for pivotally supporting said pipe carriers, and means movable by said coupler for moving said carriers transversely of the car.

2. In mechanism of the character indicated, the combination with a laterally movable car coupler, of a plurality of independently movable pipe carriers arranged upon opposite sides of said coupler, means carried by the car for pivotally supporting 80 the respective carriers so that they may swing independently, and means movable by said coupler for independently shifting said carriers in opposite directions transversely of the car.

85

3. In mechanism of the character indicated, the combination with a laterally movable car coupler, of a plurality of independently movable pipe carriers disposed upon opposite sides of said coupler, a plurality 95 of hangers pivotally supporting the respective carriers, each of said hangers being pivotally movable with respect to the car upon which it is mounted and being pivotally connected to one of said pipe carriers, and means movable by said coupler for shifting said carriers transversely of the car.

90

4. In mechanism of the character indicated, the combination with a laterally movable car coupler, of a plurality of independently movable pipe carriers disposed upon opposite sides of said coupler and adapted to be independently shifted transversely of the car upon a corresponding lateral movement of the coupler, and a plurality of 100 hangers for supporting the respective carriers, said hangers being pivotally mounted upon the car and pivotally connected to the corresponding carriers, and the lines connecting the pivot points of the respective 105 hangers being convergent upwardly, whereby said carriers normally tend to move toward said coupler.

110

5. In mechanism of the character indicated, the combination with a laterally movable car coupler, of a plurality of independently movable pipe carriers disposed upon opposite sides of said coupler and adapted to be independently shifted transversely of the car upon a corresponding lateral movement of the coupler, a plurality 120 of hangers pivotally mounted upon the car and pivotally connected to the corresponding carriers, and independent means pivotally connected to the respective pipe car- 125

130

riers and adapted to be dissimultaneously actuated by said coupler for shifting said carriers transversely of the car.

6. In mechanism of the character indicated, the combination with a laterally movable car coupler, of a plurality of pipe carriers disposed upon opposite sides of said coupler, means carried by the car for pivotally supporting said pipe carriers, and 10 means pivotally connected to the respective carriers and movable by said coupler for shifting said carriers transversely of the car.

7. In mechanism of the character indi-

cated, the combination with a laterally movable car coupler, of a plurality of pipe carriers disposed upon opposite sides of said coupler, a plurality of hangers pivotally mounted upon the car on opposite sides of the center sills thereof and pivotally connected to the corresponding carriers, and means connected to the respective carriers and extending therefrom toward the said coupler for shifting said carriers transversely of the car.

25

In testimony whereof I affix my signature.

WILLIAM KELSO.
